UNITED STATES PATENT OFFICE.

CHARLES T. BLOOMER, OF NEWARK, NEW YORK.

PAPER RECEPTACLE.

1,071,388.

Specification of Letters Patent. Patented Aug. 26, 1913.

Application filed January 17, 1912. Serial No. 671,637.

To all whom it may concern:

Be it known that I, CHARLES T. BLOOMER, a citizen of the United States, residing at Newark, in the county of Wayne and State 5 of New York, have invented a new and useful Paper Receptacle, of which the following is a specification.

This invention relates generally to receptacles constructed of paper or other suitable 10 material and particularly to means for locking the cover flaps of the receptacle in closed position.

The present invention can be used as a locking means for all kinds of paper receptacles including ice cream boxes, oyster pails, as well as other types of folding-flap receptacles not necessary to specify.

The principal object of the present invention is to provide means for easily and 20 quickly locking the receptacle in closed condition in such manner that the cover flaps shall be held positively against bulging, and that the receptacle shall be capable of being easily and quickly opened without being 25 capable of accidentally swinging open.

A further object of the invention is to effect a material saving in paper stock, equivalent to or exceeding in cost the metallic attachments employed in the present invention, whereby the cost of receptacles constructed under this invention is practically the same or lower than the cost of old forms of receptacles which are open to the objection that they are liable to bulge and accidentally open.

With the foregoing and other objects in view, which will appear as the description proceeds, the invention resides in the combination and arrangement of parts and in the 40 details of construction hereinafter described and claimed, it being understood that changes in the embodiment of the invention herein disclosed can be made within the scope of what is claimed, without departing 45 from the spirit of the invention.

In the accompanying drawing forming a part of this specification: Figure 1 is a perspective view of a receptacle constructed in accordance with the present invention, the 50 locking flaps being open; Fig. 2 is a perspective view showing the flaps folded into closed position, the folded or creased portion of the tabbed flap being folded under the tongued flap, the tongue of the latter 55 flap projecting through the opening in the tab of the former flap preparatory to bend-

ing the tongue to lock the receptacle; Fig. 3 is a view similar to Fig. 2 showing the tongue folded into locked position; Fig. 4 is a vertical section through the construction 60 illustrated in Fig. 3, showing the parts in locked condition.

Like reference numerals indicate corresponding parts in the different figures of the drawing.

The body 1 of the receptacle may be constructed in any suitable manner, such as by pasting, in the case of an ice cream pail, by folding, in the case of an oyster pail, or by otherwise arranging the blank, in accordance with the various practices of the art. The body 1 preferably is provided with upstanding side flaps 1' and 2, which are designed to be folded inward toward each other.

The reference numeral 3 indicates the tongued flap and the reference numeral 4 indicates the tabbed flap. The tongue of the flap 3 is indicated by the numeral 5 and consists preferably of a metallic strip having the clenching points or members 6, designed to be clenched through the flap 3, as shown in Fig. 1. The flap 4, is formed within the contour thereof with a tab 8 which preferably, although not essentially, 80 is substantially rectangular in shape and is separated from the flap on three sides, being joined to the flap on what may be termed its basal edge. The means for separating the tab 8 from the flap 4 on three sides preferably comprises the slotted portion 9. The slotted portion 9 is used in preference to a knife slit, as it serves to effect a complete separation of the edges of the tab 8 from the adjoining portions of the flap 4. The 95 outer end portion of the tabbed flap 4 preferably is creased along the dotted lines 10-10, so as to facilitate its bending along said lines. It will be noted that the dotted lines 10 are in alinement with the basal 100 portion or edge of the tab 8. Said basal portion of the tab 8 is uncreased, as shown. The tab 8 is formed with a cut away portion or tongue opening 11 which preferably is tapered in form, as shown; the wide portion of said opening 11 being substantially in alinement with the creased portions 10, although this location of the opening is not essential.

Particular attention is directed to the fact 110 that although the flap 3 is relatively short, while the flap 4 is relatively long, both of

the flaps have their free ends terminating considerably short of the respective sides of the receptacle, the free ends only of the flaps 3 and 4 being adapted to overlap at 5 an intermediate point. Thus, a material saving in stock is provided.

Constructed as described, the manner of manipulating or closing the receptacle is as follows: The side flaps 1 and 2 are first 10 folded downward toward each other in the usual manner. The locking flaps 3 and 4 are then folded toward each other in such manner that the outer creased end of the flap 4 is directed underneath the tongued flap 3, 15 the tab 8 of said flap 4 projecting on the outside of said tongued flap 3. The tongue 5 of the flap 3 when the outer creased portion of the flap 4 is first fitted under the flap 3, is directed through the tab opening 20 11. By pushing downward on the top of the box, the flaps assume the position illustrated in Fig. 2, with the tongue 5 projecting through the tab opening, the creased portion 4' of the flap 4 being disposed underneath the flap 3, and the uncreased tab 8 projecting on the outside of the flap 3. It 25 is now only necessary to slip the finger beneath the tongue 5 and bend it over into the position illustrated in Fig. 3 of the 30 drawing.

An important feature results from the provision of fold lines extending from the ends of the U-shaped slit forming the tab to the side edges of the flap 4, in that, when 35 the flaps 3 and 4 are closed or folded over the mouth of the receptacle, the tongue 5 may be passed or projected through the aperture or opening 11 of the tab without bending either the tab or tongue, the free 40 end of the tabbed flap 4 being flexible or foldable away from the tab for this purpose. In a device of this character it is essential that the tab be as small as possible, it being noted that the base or butt end of the tab 8 45 is weakened by the aperture or opening 11, and it is therefore desirable that the tab remain unfolded or uncreased. With the present arrangement, it will be clearly apparent that the tab 8 remains in the plane 50 of the flap 4 under all conditions, and is not folded or bent, the tongue 5 being adapted to pass through the tab without either of them being folded or bent. The tongue 5 is only bent after the flaps 3 and 4 are in 55 position, so that the tab 8 will be of the greatest strength possible, as is essential.

The free end or portion 4' of the flap 4 is readily flexible or foldable away from the tab 8 to permit of the insertion of the tongue 5 through the tab in the manner specified. 60

The locking means of the present invention are strong, simple, durable and inexpensive in construction, as well as thoroughly practical and efficient in operation.

The locking device can be readily unlocked by bending up the tongue 5. When the tongue 5 is bent on itself in the manner indicated, it engages the narrow end of the tapered tongue opening and thus centers 70 itself properly in the tongue opening without being permitted to move sidewise relatively to the opening.

The tapered opening 11, which has its edges diverging from the free end of the tab 8, is of advantage, for the reason that 75 the larger or inner end of the opening 11 permits the tongue to be readily inserted therethrough and then bent back, the bend will work outwardly between the edges of the opening 11 and will thus bring both of 80 the flaps 3 and 4 in proper position relative to each other. Thus, although only the free ends of the flaps 3 and 4 are overlapped, both of the said flaps will be locked against lateral shifting movements. The provision 85 of the tongue 5 carried by the free end of the flap 3 and the provision of the tab 8 at the free end of the flap 4 provides for a saving of stock, and also permits the flaps to be locked in engagement in such a manner 90 as to prevent shifting movements at either flap.

What is claimed as new is:

A receptacle having flaps, one flap having a tongue at its free end, and the other having a U-shaped slit at its free end forming a tab, an aperture at the base of the tab and fold lines between the ends of the slit and side edges, whereby the free end of the tabbed flap is foldable downwardly from 100 the tab to pass under the tongued flap and to permit the tongue to pass through the said aperture when the flaps are closed, without bending the tab or tongue, the tab swinging onto the tongued flap. 105

In testimony that I claim the foregoing as my own, I have hereto affixed my signature in the presence of two witnesses.

CHARLES T. BLOOMER.
